UNITED STATES PATENT OFFICE.

JESSE M. CURTICE, OF LOUISVILLE, KENTUCKY.

CHURN.

SPECIFICATION forming part of Letters Patent No. 409,020, dated August 13, 1889.

Application filed September 15, 1888. Serial No. 285,437. (No model.)

To all whom it may concern:

Be it known that I, JESSE M. CURTICE, a resident of Louisville, in the county of Jefferson and State of Kentucky, have invented certain new and useful Improvements in Churns; and I do hereby declare the following to be a full, clear, and exact description of the invention, such as will enable others skilled in the art to which it appertains to make and use the same.

10 My invention relates to an improvement in churns, and particularly to a type in which the body of the churn is rocked to agitate the cream and produce butter.

One object of my present invention is to 15 produce a churn of the character named which may be operated by foot-power, the operator being seated, so as to engage peculiarly-connected pedals with one or both feet to rock the body of the churn.

20 A further object is to provide an oblong body with rockers that are adapted to facilitate the easy-rocking movement of said body, and, further, to furnish a simple means for locking these rockers from a rolling movement when it is desired to retain the body of 25 the churn in a stationary position.

A further object is to provide a cheap, convenient, and secure means for the attachment of a discharge-nozzle to the body of the churn, 30 which is available for the draining or removal of buttermilk from the churn-body after the churning operation has been completed.

35 A further object is to furnish a rocking churn-body with a hollow pendulum which can be weighted to suit the operator.

To effect the objects indicated, the invention consists of certain features of construction and combinations of parts, which will be hereinafter described, and pointed out in the 40 claims.

45 Referring to the drawings, Figure 1 is a side elevation of the churn. Fig. 2 is a top plan view. Fig. 3 is a cross-section of the churn through its center of length. Fig. 4 is a side elevation in section, taken on a line $x-x$, or through the center of width of the churn. Fig. 5 is a detached view of one of the churn-rockers.

The churn-box A is preferably made of 50 wood, and consists of a shell or case of oblong form having its ends rounded to avoid abrupt corners. The sides of the box A are grooved

to receive the top, bottom, and end walls. On the top a pair of adjustable lids a are placed to cover an orifice made through the top wall 55 for introduction of cream to be churned. The construction of these lids and their retaining-cleats a' has been already shown by me in a previous patent, hence it is not necessary to minutely describe them in this connection. 60

The churn-box A is mounted on a frame B, that is of proper height and width to support said box on two rockers C to permit a rocking action of this receptacle that will agitate its contents. On the top surface of the frame B 65 two track-plates D are fixed. These are of suitable width and length to afford tracks or bearings for the rockers C. Each has two ribs b formed on its top face to produce longitudinal grooves, in which the rockers C may 70 roll and be prevented from lateral displacement.

One of the track-plates D has an elongated slot c cut through it near its center of length, which slot is located outside of and parallel 75 to the ribs b , and the plate D is cut away below said slot to afford an open recess b' the width of the plate. A locking-block D' is provided, which is made of a suitable thickness to fit loosely in the slot c , and of such 80 breadth, considered lengthwise of said slot, as to be permitted to slide in the same. There are laterally-projecting flanges c' formed on the block D', which are located to move freely in the recess b' . 85

Upon the rocker C, that is located on the slotted track-plate just described, a lug c^2 is formed or secured, which is preferably made oblong with parallel top and bottom sides, to allow it to engage an open slot c^3 , cut in the 90 adjacent edge of the vertically-projecting locking-block D' when the churn-body is level and said block is slid toward the lug, thus securing the churn-body in level position when this is necessary, to facilitate the removal of 95 the churned butter therefrom.

As will be seen, the rockers C are furnished with lateral projections d at their ends, which are flattened to produce flanges which extend at right angles to their extremities. These 100 flanges are perforated and countersunk for the reception of screws, whereby they are secured in proper position oppositely upon the sides of the churn-box A, their bearing curved

surfaces being so located with regard to the top or bottom sides of the box as to support the same level, transversely considered.

The arched surface of the rockers C is provided with spaced toothed projections e, that are adapted to register with a series of recesses made in the track-plates D when the box A of the churn is rocked, this engagement of teeth and receiving-sockets on the rockers and plates insuring a rocking motion by prevention of slipping when the butter is forming and being gathered into a lump, which would have a tendency to overweight the end of the churn-box to which it is rolled.

15 The treadles E are in pedal form, and have a removable hinged connection with the stretcher-bar f of the frame. These pedals have been shown in another patent; hence I do not make special claim to their specific 20 construction in this case.

25 The pedals E are connected to the churn-box A at the points g, or at the terminal ends of the rockers C, where studs h are inserted in these ends to afford a pivotal connection of the pedal-rods F therewith, said rods having hooked engagement with the loops G, which have their hooked ends loosely attached to the edge of the pedals at a proper point to permit the pedals to be freely vibrated alternately, and thus communicate a 30 rocking motion to the churn-box A.

35 In order to assist the rocking action of the churn, it is preferred to utilize the pendulum I. This device is not broadly new, I am aware; but I have for the purpose of saving metal in its construction devised the hollow weight J, as shown, which is preferably made of two half-shells that are joined to produce a hollow receptacle, in which any heavy material may be 40 introduced to give proper weight. The pendulum itself is merely a shell, and by loading the same with scrap metal, which can be introduced from the top or placed in the half-sections before the latter are connected together, it can be more or less weighted as 45 necessity demands.

Having fully described my invention, what I claim as new, and desire to secure by Letters Patent, is—

50 1. In a churn, the combination, with a churn-box and a supporting-frame, of two rockers secured at their ends to the box, with their curved faces resting on the supporting-frame, a movable block adapted to engage a

projection carried by the churn-box for locking the latter against movement, connecting-rods attached to the churn body, and treadles connected to the lower ends of the connecting-rods, substantially as set forth. 55

2. In a churn, the combination, with a churn-box and a supporting-frame, of two rockers secured at their ends to the box, with their curved faces resting on the supporting-frame, a movable locking-block mounted in the frame and adapted to engage a projection 60 on one of the rockers for locking the churn-body in a horizontal position, connecting-rods attached to one of the rockers at or approximately at the opposite ends thereof, and treadles attached to said connecting-rods, substantially as set forth. 70

3. In a churn, the combination, with a supporting-frame having track-plates thereon, and a churn-box having rockers, the latter having teeth adapted to register with indentations in the track-plate, of the connecting-rods attached at or near the ends of one of said rockers, a device for locking one of the rockers to the supporting-frame, and treadles connected to the lower ends of the connecting-rods, substantially as set forth. 75 80

4. In a churn, the combination, with a supporting-frame and a churn-box having a weight depending from the bottom thereof, rockers secured to the sides of the box, with their curved faces resting on the supporting-frame, and a movable block adapted to engage a projection carried by the churn-box for locking the latter against movement, of rods attached to the churn-box near the ends 85 of one of the rockers, and treadles attached to the lower ends of the rods, substantially as set forth. 90

5. The combination, with a churn-box that is made to rock endwise on rockers and track-plates, of a rocker having a projecting lug, a slotted and recessed track-plate, and a locking-block which is adapted to slide in the slot of the track-plate and is also slotted to engage the lug of the rocker, substantially as 95 100 set forth.

In testimony whereof I have signed this specification in the presence of two subscribing witnesses.

JESSE M. CURTICE.
